AARON M. SPRINGER,
Inventor.

By *Joseph L. Lichten* Atty.

UNITED STATES PATENT OFFICE.

AARON M. SPRINGER, OF PORTLAND, OREGON, ASSIGNOR TO OREGON WOODENWARE MFG. CO., A CORPORATION OF ILLINOIS.

IRONING-BOARD.

1,369,942.

Specification of Letters Patent. Patented Mar. 1, 1921.

Application filed November 26, 1917. Serial No. 203,994.

To all whom it may concern:

Be it known that I, AARON M. SPRINGER, a citizen of the United States of America, residing in Portland, in the county of Multnomah, in the State of Oregon, have invented 5 certain new and useful Improvements in Ironing-Boards, of which the following is a specification, reference being had to the accompanying drawings.

10 My invention relates to improvements in ironing boards of that general description in which an ironing board proper is provided with collapsible supporting mechanism that is always attached to it ready for use, but 15 which may be folded up into small compass convenient for storing the device out of the way when it is not required for service.

Among the various objects of my invention, those regarded as most important are 20 the production of such a device of extreme lightness, simplicity and rigidity of structure, and the promotion thereby of economy in the manufacture of the article and of its durability and efficiency in use. How the 25 objects referred to are attained will be best understood from the following specification wherein that which constitutes my invention is first described in detail and afterward succinctly set forth in the appended 30 claims.

In the accompanying drawings,

Figure I is a side elevation of my board having its supporting members expanded to the several positions which they occupy 35 when the board is in use.

Fig. II is an end elevation partially in section taken on the line II—II of Fig. I.

Fig. III is a detail section on an enlarged scale taken on the line III—III of Fig. II.

40 Fig. IV is a bottom plan view of my device complete, showing in full lines the supporting members folded against the bottom of the board and within the compass of its periphery, and showing in dotted lines lateral expansion of the outside legs.

Referring to the numerals on the drawings, 1 indicates an ironing board proper which is preferably made of wood, and may be of any usual or preferred shape and dimensions suitable for the purposes required of it.

Upon the bottom of the board 1, and operatively secured to it so that they may be conveniently folded against it when the 55 board is not in use, I provide an assemblage

of supporting members, comprising outside legs 2 and 3 which coöperate as a pair, and a third or intermediate leg 4. The legs 2, 3 and 4 constitute when expanded a tripod support for the board 1, and are adapted 60 to be expanded into operative positions as shown in Figs. I and II, by a pair of braces 5 and 6, operatively extending between the legs 2 and 3, respectively, and the bottom 65 of the board 1, and a pair of tension rods 7 and 8, connecting the free end of the leg 4 to the legs 2 and 3, respectively, substantially at their respective points of connection with the braces 5 and 6.

The effect of the structure described, when 70 its parts are in the expanded position described, is that of a truss section, affording to the supporting frame a maximum of rigidity in proportion to the lightness of the members contributing to that end.

75 The legs 2 and 3 are carried upon a hinged or rocking member, preferably a cross-bar 9, that is preferably made of wood provided with terminal trunnions 10 working in journal bearings 11, that consist preferably of 80 properly apertured blocks secured, as by screws 12, against the bottom of the board 1.

I prefer to secure the legs 2 and 3, respectively to the cross-bar by any suitable means which will admit also of such relatively oscillatory movement of the legs as will permit them to be expanded to the positions which they occupy as shown in Fig. II, or as is indicated in dotted lines in Fig. IV. The obvious advantage is derived therefrom of making it possible to spread the feet of the legs sufficiently apart in service to afford a wide base of support for the board 1. Bolts 15, passing through the legs 2 and 3, respectively, and the cross-bar 9, 95 afford simple and effective means for securing the legs to the cross-bar to the effect above described.

In coöperation with the legs 2 and 3, I prefer to provide transverse braces 16 and 100 17 that are in effect parts of the legs, being secured at their lower ends to their respective legs as by bolts 18 and 19, respectively. Their upper ends converge close to the bottom of the board 1, and are preferably 105 loosely pivoted to the cross-bar 9. They are nicely adjusted in length and preferably provided with transversely beveled ends 21 and 22, respectively, so as to insure a frictional engagement with the bottom of the 110

board 1 when they are set in the positions shown in Figs. I and II. By reason of their disposition relatively to their respective legs and to the board 1, they are made to contribute, through advantageous distribution of the stress of a load laid upon the board, to the rigidity of the legs 2 and 3 in service, and to the firm support of the board. A metal bearing-plate 23 is preferably fixed to 10 the bottom of the board 1 to receive engagement of the ends 21 and 22 and to resist the wear which such engagement offers.

It was specified in the last paragraph that the braces 16 and 17 are preferably loosely 15 pivoted to the cross-bar 9. With a further object in view, I prefer to effect the loose pivoting of those members to the cross-bar by aid of a pair of metal plates 25 and 26 secured as by rivets 27 to the respective 20 braces 16 and 17 and hinged together, as by a pintle 28, in such manner as to permit of the shearwise movement of the plates 25 and 26. These plates project beyond the edges of their respective braces 16 and 17 25 as shown in Figs. II and IV, so as to admit of the introduction between them of a spacing-member 30. The spacing-member 30 is preferably a screw screwed into the cross-bar 9 as clearly shown in Fig. III, and may 30 be provided with a broad head, or preferably with a washer 31, as shown in Fig. III, to serve the purpose of loosely confining the plates 25 and 26 in their movements to the cross-bar 9.

35 The presence of the spacing-member 30 between the hinged plates 25 and 26 provides, in addition to the loose pivotal connection which it affords between the braces 16 and 17 and the cross-bar 9, means where- 40 by the legs 2 and 3 may be expanded at will, within a limit of expansion imposed by contact between the member 30 and the crotch formed by the pintle 28 between the plates 25 and 26, said expansion being automatic 45 whenever the legs 2 and 3 are brought into position substantially at right angles to the board 1, (compare Figs. I and II). The effect of automatic expansion last described is produced by the engagement of the bot- 50 tom of the board 1 or plate 23 thereon with the ends 21 and 22 of the braces 16 and 17 so that those braces are driven endwise by such engagement, the pintle 28 being thereby urged toward the screw 30 with the ef- 55 fect of causing the screw 30 to act as a wedge so as to separate the plates 25 and 26. The plates 25 and 26 work upon their hinge connection made by the pintle 28 and when spread by the member 30, force the legs 2 and 3 apart.

The leg 4 is hinged to the bottom of the board 1, preferably by aid of a pin 35 pass- 60 ing through a pair of blocks 36 secured, as by screws 37, to the bottom of the board 1.

65 The pin 35 is preferably located as close to

the axle of the cross-bar 9 as may be con- 70 venient, and the length of the leg 4 is such as to bring its foot 38 nearly vertical to the end of the board 1 which it supports.

The tension rods 7 and 8 extend from a point of connection 39 with the leg 4 near its foot 38 to the bolts 18 and 19, respectively, to which they are united in effect by a loose connection, for example chains 40 and 41, respectively. The chain connection 75 is preferred because of its convenient flexibility, but is intended to be only representative of any flexible connection suitable for the purpose.

It has just been stated that the rods 7 and 80 8 are in effect connected to the bolts 18 and 19. In respect to detail, however, I prefer to provide upon the ends of the respective braces 5 and 6 hinge terminals 42 and 43, which being made of metal afford preferred 85 means of hinging the braces 5 and 6 to the bolts 18 and 19, respectively, and also a convenient means to which the chains 40 and 41 may be secured at one end, respectively.

The terminals 42 and 43 may be of any 90 suitable and preferred shape, but I prefer to make them in the form of cheek plates, and to provide each of them with a trans- 95 verse flange 44 which, under the tension of rivets 45 by which they are secured to the 95 braces 5 and 6, respectively, serves to hold the securely in alinement with the braces.

The relative lengths of the legs 2 and 3, and 4, and of the rods 7 and 8 being prop- 100 erly adjusted, it remains only to provide in the braces 5 and 6 an accurate adjustment of length in order to effect a rigid assem- blage of the members when these braces are adjusted to their holding positions. This position is determined by an engaging mem- 105 ber 47 which may consist of a cleat of wood secured to the bottom of the board 1 and preferably notched as indicated at 48, to engage and hold the ends of the respective braces 5 and 6. Incidentally the cleat 47 110 and a like cross piece 49 serve to lend strength to the board 1, to prevent its splitting. The braces 5 and 6 are united near their free ends as by a yielding, preferably, 115 metallic bar 50, adapted from its yielding nature to afford a slight hinged effect be- 120 tween the bars to accommodate expansion of the legs 2 and 3. The bar 50 also affords a convenient means for engagement with it of a hook 51 depending from the bottom of the board 1, and which may be used, if de- 125 sired, to hold the ends of the braces 5 and 6 in engagement with their notches 48. A sufficiently secure engagement may, how- ever, generally be attained by stress of the members, and without the need of the hook 51.

By reason of the presence of the bar 50 uniting the free ends of the braces 5 and 6, those braces are made to act substantially 130

- as a unit. In that capacity they contribute to the convenience of operation of my device, in that they afford means for operating the supporting mechanism of the board 5 from a single point. That is to say, in operation, it is necessary only to manipulate the free ends of the united braces 5 and 6 in order to set up the board for use. To accomplish that purpose, it is necessary only 10 for the operator gently to force the ends of the braces toward the member 47, to accomplish the result of spreading the legs 2 and 3, setting the leg 4 into position, and producing the requisite tension upon the rods 7 15 and 8. The entire operation following the single manipulation described, is accomplished automatically. Also when the ends of the braces 5 and 6 are adjusted to the notches 48 they serve to secure the various 20 members of the supporting mechanism in operative position from a single point. The expansion of the members into a truss is accomplished by effecting engagement under stress between the ends of the braces 5 and 25 6 and notches 48, and collapse of the supporting mechanism may be instantly accomplished by disengagement of the members at that point, under action so obtained by relief of stress.
- 30 The operation of my device, will, it is believed be understood from the foregoing specification without further description.
- What I claim is:
1. The combination with a board and its supporting mechanism comprising a cross-bar mounted thereon by means admitting of its rocking movement about its longitudinal axis, of a pair of legs each hinged to the cross bar, and means adapted automatically to expand the free ends of said legs whenever the cross bar is actuated so as to bring the legs substantially at right angles to the board.
  2. The combination with a board and its supporting mechanism comprising a cross-bar mounted thereon by means admitting of its rocking movement about its longitudinal axis, of a pair of legs each hinged to the cross-bar, braces extending from the legs, respectively, toward the cross-bar and loosely pivoted to the cross-bar and hinged to each other, and means compelling the separation of the legs whenever the cross-
- bar is rocked upon its axis to bring the legs substantially at right angles to the board. 55
3. The combination with a board and its supporting mechanism comprising a cross-bar mounted thereon by means admitting of its rocking movement about its longitudinal axis, of a pair of legs each hinged to the cross-bar, braces extending from the legs, respectively, toward the cross-bar and loosely pivoted to the cross-bar and hinged to each other, and means compelling the separation of the legs whenever the cross-bar is rocked upon its axis to bring the legs substantially at right angles to the board, 60 said means consisting of projections of the braces beyond the cross-bar and into operative engagement with the board. 65
4. The combination with a board and its supporting mechanism, comprising a cross-bar mounted thereon by means admitting of its rocking movement about its longitudinal axis, of a pair of legs each hinged to the cross-bar, braces extending from the legs, respectively, toward the cross-bar, a hinge uniting the contiguous ends of the braces and a spacing-member on the cross-bar serving loosely to secure the hinge to the cross-bar and to limit the expansion of the legs. 70
5. The combination with a board and its supporting mechanism, comprising a cross-bar mounted thereon by means admitting of its rocking movement about its longitudinal axis, of a pair of legs each hinged to the cross-bar, braces extending from the legs, respectively, toward the cross-bar, a hinge uniting the contiguous ends of the braces and a spacing-member on the cross-bar serving loosely to secure the hinge to the cross-bar and to limit the expansion of the legs, 75 the ends of the braces projecting beyond the cross-bar and serving through engagement with the board to spread the legs automatically whenever the said projecting ends are brought into engagement with the surface of the board by the swinging of the cross-bar. 80
- In testimony whereof, I have hereunto set 85 my hand in the presence of two subscribing witnesses.
- AARON M. SPRINGER.
